(57) CLAIM

The ornamental design for a box with electronic screen, as shown and described.

DESCRIPTION

FIG. 1 is a front right perspective view of a box with electronic screen, showing my new design in an open position;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a left side perspective view thereof showing the box with electronic screen in another open position; and, FIG. 9 is a right side perspective view thereof showing the box with electronic screen in a closed position.

The broken lines of even length depict portions of the box with electronic screen that form no part of the claimed design.
